Inventor
E. BAST

UNITED STATES PATENT OFFICE

EMIL BAST, OF BERLIN, GERMANY

SANITARY CLOSET

Application filed May 22, 1928, Serial No. 279,798, and in Germany March 31, 1928.

This invention relates to a sanitary closet and its object is to provide on the one hand improved hygienic conditions especially in regard to avoiding the issue therefrom of disagreeable or noxious gases, and on the other hand a simple construction and a simple configuration of the portions utilized.

An essential feature of the closet according to the present invention is that the pan is divided by an upright partition into two compartments one behind the other, of which the front compartment serves as a urinal and remains permanently open, whilst the rear compartment serving as the actual closet basin can be closed by a horizontally guided sliding cover.

The sliding cover, which is located beneath the seat and suitably is composed of earthenware, porcelain or other similar resistant material, can be displaced by means of an external handle, the displacement preferably effecting also the control of the water flush.

The actual closet basin can be closed beneath by a flap and is connected to a ventilation pipe. This ventilation pipe may be a laterally situated continuously extending fall pipe by means of which any foul gases are constantly sucked upwards.

As the closet basin is constantly closed, empty, odourless and protected against freezing, the soil pipe need merely be provided in the basement, where it is connected to the house drain, with a closure contrivance.

When conditions so demand, merely household slopes can suffice for flushing the closet.

On the accompanying drawings, in Figs. 1 to 4 a constructional example of a water closet according to the invention is illustrated, and in Fig. 5 the application of the invention to a dry closet is shown. In these drawings:—

Fig. 1 is a side elevation;

Fig. 2 a section taken along the diverted line A—B of Fig. 1;

Fig. 3 a plan, and

Fig. 4 a vertical longitudinal section;

Fig. 5 is a vertical longitudinal section on a smaller scale showing the dry closet.

In the construction shown in Figs. 1 to 4, the pan 1, which is fitted into a socket 3 of the

soil pipe 4, is divided by an upright partition 5 into two compartments. The front compartment 6, which is intended for urination, remains constantly open and is closed at the bottom by a ball valve 7. The rear compartment constituting the actual closet basin 8 is closed by a sliding cover 9, which is horizontally displaceable beneath the upwardly lifting pivoted seat 10. The displacement of the sliding cover, which is composed of a water and acid resistant material such as porcelain and suitably has a rearwardly slightly upwardly sloping upper surface, is effected by a handle. In the construction illustrated, the handle consists of a knob 11 situated laterally beneath the seat, and is provided on a rack 12. Lateral links 13 connected to this rack 12, which as shown in Fig. 2 slides on a dovetailed guide 14, engage by means of pins or studs 15 in holes in the sliding cover 9, so that on displacement of the rack 12 the cover is displaced therewith, without an absolutely rigid interconnection of the two parts being provided. The closet basin 8 is closed at the bottom by a flap 16, which can be turned over intermittently from the exterior, after use of the closet, by means of the weighted arm 17 (Fig. 1), whereby the upper side of the flap with the excreta becomes directed downwards and permits the latter to drop off, whilst the previously clean underside of the flap becomes directed upwards.

The rack 12 gears by its teeth with a pinion 18 (Figs. 1 and 2), which is so mounted on the plug 19 of a cock which controls the water flush that whenever the sliding cover 9 is closed or opened the flushing water is turned on and off, so that the basins 6 and 8 are thereby flushed. In addition the basin 6 can be independently flushed by water from a branch pipe 21 (Fig. 3), controlled by hand by a knob 20 (Fig. 1).

Connected to the vertical fall and ventilation pipe 22, which suitably is located at the side of the closet, is a ventilating pipe 23, leading to the basin 8. Below in the soil pipe 4 ventilation is provided by a branch pipe 24. The ventilating branch pipe 23 can be closed by a butterfly valve 33 which is positively con-

nected to the sliding cover 9. The handle 11 for displacing the sliding cover and the handle 17 for displacing the lower closure flap 16 may be positively interconnected.

5 Fig. 5 illustrates a dry closet constructed in accordance with the invention. Here, as in the water closet, the pan is formed with two compartments or basins 6 and 8, of which one 8 can be closed by the sliding cover 9 displaceable from the exterior. In a casing 25, supporting the basins 6 and 8, is contained a receptacle 27 for receiving the excreta, this receptacle being introduced and withdrawn through an opening, capable of being closed 15 by a door or flap, in the wall of the casing, conveniently an opening 26 in the rear wall thereof. For receiving urine draining from the front basin 6, is provided a separate receptacle 28 loosely thrust into place from the front. This receptacle 28 can when necessary be easily removed and emptied. The receptacle 27 is removed after pushing the closet away from the wall against which it stands, after the pipe section 32 of the closet formed 25 with a socket 29 has been disconnected from the fixed ventilating pipe 31. For purposes of ventilation a branch pipe 30 leads from the pipe section 32 to the basin 8. Gases ascending from the receptacle 27 below also 30 have access. The ventilating pipe can at times be closed by a butterfly valve 34. In the form shown in the drawings, the dry closet is easily transportable, so that it is 35 capable of manifold use. It can be used with all kinds of sewers by substituting a hopper for the receptacle 27.

Claims:

1. In a sanitary closet, a pan, a transverse upright partition in and dividing said pan into a front and a rear basin, a cover closing said rear basin, and means guiding said cover to slide above said rear basin in the longitudinal direction of the closet.
2. In a sanitary closet, a pan, a transverse upright partition in and dividing said pan into a front and a rear basin, a cover closing said rear basin, means guiding said cover to slide above said rear basin, a water flush, and means operating said water flush by and during sliding of said cover.
3. In a sanitary closet, a pan, a transverse upright partition in and dividing said pan into a front and a rear basin, a cover closing said rear basin, means guiding said cover to slide above said rear basin, means closing the bottom of said rear basin, a ventilating fall pipe alongside said closet, a branch ventilating pipe leading from said rear basin beneath said cover to said fall pipe, and a branch ventilating pipe leading from said pan beneath said bottom closure means of said rear basin to said fall pipe.
4. In a sanitary closet a fixed basin, an upwardly lifting pivoted seat, a sliding cover

situated beneath the said seat and a handle situated laterally for displacing said cover.

5. In a sanitary closet, a pan, a transverse upright partition in and dividing said pan into a front and a rear basin, a cover closing 70 said rear basin, means guiding said cover to slide above said rear basin, an invertible flap closing the bottom of said rear basin, a ventilating fall pipe alongside said closet, a branch ventilating pipe leading from said rear basin beneath said cover to said fall pipe, 75 and a branch ventilating pipe leading from said pan beneath said invertible flap to said fall pipe.

In testimony whereof I have signed my so name to this specification.

EMIL BAST.
